QUILT MARKER

Ora Zoe Dell Johnson, Mutual, Okla.

Application March 29, 1948, Serial No. 17,787

6 Claims. (Cl. 33—27)

1

This invention comprises novel and useful improvements in a quilt marker and more specifically pertains to a marking device for selectively producing a plurality of parallel straight lines or concentric arcuate lines upon a quilt to assist in stitching the same.

An important object of the invention is to provide a device for simultaneously producing a plurality of parallel straight lines upon the surface of a quilt or the like.

A further object of the invention is to provide a device in accordance with the foregoing object which is capable of producing a plurality of concentric arcs of any desired relative spacing upon the surface of a quilt or the like.

An important feature of the invention is the provision of an apparatus having a base member, a marker holder member mounted thereon, together with aligned openings in the base and holder for positioning the marker for operation upon the surface of a material to be marked.

A further feature of the invention resides in the provision of an improved holder consisting of a pair of complementary plates having notches in their adjacent edges together with clamping means for frictionally gripping and securing a plurality of markers at any desired longitudinal spacing in the holder plate.

A still further feature of the invention resides in the provision of a marking device as set forth in the preceding paragraphs, wherein the base is provided with a plurality of longitudinally spaced apertures for receiving the ends of markers, together with indicia or scale means carried by the base to facilitate the spacing of the markers at desired distances from each other, together with a clamping holder mounted above the base for frictionally securing a plurality of markers above the apertures of the base.

Yet another important feature of the invention resides in the provision of a marker whose base portion is provided at one end with a guide shoulder thereon whereby rectilinear movement of the marker along a guide rail and over a surface to be marked may be readily obtained.

Yet another important feature of the invention resides in the provision of a marker having a base member one of whose ends is provided with a pivoting bore therein whereby arcuate movement of the marker about the bore may be readily effected for producing arcuate concentric lines by the markers carried by the instrument.

And a final important feature of the invention to be specifically enumerated herein resides in the provision of a marking device which shall be of

2

light weight, inexpensive and simple construction, easily adjusted to receive any desired number of markers, may be readily operated to selectively produce straight or arcuate lines, and which shall be highly efficient and durable for the purposes intended.

These, together with various ancillary features and objects of the invention which will later become apparent as the following description proceeds, are attained by this device, a preferred embodiment of which has been illustrated by way of example only in the accompanying drawings, wherein:

Figure 1 is a side elevational view of the device; 15 Figure 2 is a top plan view of the device, a part of the holder being broken away to show the upper surface of the base thereof;

Figure 3 is a vertical transverse sectional detail view taken substantially upon the plane of 20 the section line 3—3 of Figure 1 and illustrating particularly the manner of securing the holder to the base;

Figure 4 is a further vertical transverse sectional view taken substantially upon the plane 25 of the section line as indicated at the numeral 4 in Figure 6;

Figure 5 is a top plan view showing the manner of applying the device to a guide rail of a holding frame for marking a quilt with parallel 30 straight lines thereon;

Figure 6 is a perspective view showing the device in operative position upon a guide rail for producing a plurality of parallel lines upon the surface of a quilt or the like; and,

35 Figure 7 is a fragmentary top plan view showing the device mounted upon the surface of a quilt for producing concentric arcuate fanlike lines thereon.

Referring now more specifically to the accompanying drawings, wherein like numerals designate similar parts throughout the various views, attention is directed chiefly to Figures 1, 2 and 6 wherein the marking device is shown as comprising a base 10 which is provided with a plurality of 45 equidistantly spaced apertures 12 throughout the length thereof, which apertures are appropriately placed upon an indicia or scale 14 to assist in obtaining the desired spacing of the markers as set forth hereinafter.

At one end, the base 10 is provided with an upwardly offset or recessed portion 16 and is provided at that end with a terminal portion 18 having a rounded margin and provided with a pivot bore 20. At its other end, the base 10 is provided with an upwardly extended wall 22 which extends

horizontally outwardly from the base as at 24 and is provided with a further upwardly extended portion 26, the portions 22 and 24 forming a guide shoulder as set forth hereinafter.

A supporting standard is mounted upon the offset or recessed portion 16 of the base 10. This standard, as shown in Figures 3 and 6, is preferably formed of a single strip of material, which has a central horizontal end portion 28 with upwardly extending sides 30, which at their upper ends are bent inwardly toward each other as at 32 to form a generally rectangular enclosure for a purpose to be later set forth. The inner ends of the upper portion 32 are bent in parallel relation and provide upwardly extending gears 34. The base portion 28 rests upon the upper surface of the offset portion 16 of the base 10, while a U-shaped plate having upper and bottom walls 36 and 38 respectively and an end wall 40, constitutes a strengthening and reinforcing member which is snugly received within the rectangular opening defined by the above mentioned walls, 28, 30 and 32. This U-shaped member has its bottom portion 38 rigidly secured to the bottom wall and to the offset portion 16 of the base 10 as by means of a screw 42. It will thus be seen that the U-shaped member and the standard are rigidly attached to the base and constitute a box-like rigid supporting standard extending upwardly from one end thereof.

The above mentioned portion 26 at the other end of the base 10 likewise extends upwardly to constitute a further supporting standard, and as shown in Figures 4 and 6 is twisted at right angles upon itself to provide an ear 44 which is in substantial alignment with and in the same vertical plane as the central lines through the above mentioned ears 34.

The holder is provided for adjustable attachment to the upstanding standard members at the ends of the base 10. This holder consists of a pair of substantially identical horizontally extending clamping members or plates 46 and 48 whose adjacent edges are provided with semi-circular notches 50 in alignment and register with each other to form recesses for receiving any suitable markers therein such as pencils 52 or the like. It should be here noted that the plurality of recesses or notches 50 are in substantial alignment with the plurality of apertures 12 of the base member 10, whereby a marker pencil 52 may be securely clamped in the complementary notches of the two supporting plates, and rigidly held thereby, with the pencil point extended through the apertures 12 and projecting therebeneath as shown in Figure 4, for marking the surface of the quilt 54 or any surface which it is desired to mark. To adjustably secure the holder plates 46 and 48 to the base 10, the inner edges of the extremities of the plates are provided with upstanding ears 56 one of which has an internally screw threaded aperture, while the other ear and the intermediate ears 34 and 44 have apertures in alignment therewith. A wing bolt 58 extends through these apertures into the screw threaded aperture for frictionally clamping the ears to each other, and thereby adjustably tensioning the plates or clamping strips 46 and 48 toward each other to thereby adjustably cause a frictional gripping action between the holder plates and the markers 52. If desired, the outer end surface of the ear 44 may be notched inwardly therefrom as at 45 in Fig. 1 or provided with a hook-like notch whereby the holder plates 46 and 48 may be pivoted about the

wing bolt 58 at their left ends as viewed in Figure 6, to thereby quickly release the right end of the holder from its fastening engagement with the standard 26.

From the foregoing, the manner of inserting any desired number of markers and obtaining any desired spacing of the markers in the marking device will be readily understood and further explanation regarding the same is believed to be unnecessary.

Attention is now directed to Figure 5 to illustrate a suitable manner of employing the device for most efficient results. For this purpose, a quilt 54 is mounted in any suitable supporting frame, and the guide rail 62, which in some instances may be a part of the supporting frame for the quilt, is suitably positioned upon or adjacent an edge of the quilt or surface which it is desired to mark. This guide rail 62 may be of any desired length, and may likewise be formed of a plurality, few or more, longitudinally aligned sections to provide a rail of the requisite length. For this purpose, as shown in Figure 5, a section of the rail 62 may be abutted against a further section 63, and one of these sections such as that indicated at 62 may be secured thereto as by screws or rivets 64, a fastening plate 66.

The connecting plate 66 extends beyond the end of the section 62 and overlies the section 63, and in its overlying portion is provided with a plurality of keyhole slots 68 for the reception of headed fastening members 70, and of a wing bolt 72, whereby the sections may be readily and rigidly secured to each other to provide a guide rail of the necessary length. The shoulder portion consisting of the walls 22 and 24 of the base 10, is then seated upon the guide rail 62 as indicated in Figures 5 and 6, whereby the base extends substantially perpendicular to the guide rail 62 and may be moved longitudinally thereof, whereby each of the markers carried by the base and holder will produce a plurality of parallel marked lines 74 when the marking device is moved in the direction of the arrow 76. Obviously, any desired spacing of lines 74 may be obtained by appropriately positioning the marking pencils 52 within the holder plates 46 and 48 of the device.

Alternatively, the device may be employed to produce simultaneously a plurality of concentric arcuate or fan-like lines 78 by merely securing the device by a pin extending through the pivot bore 20 thereof, and then oscillating or arcuately moving the marker device about the pivot pin. Thus, parallel straight lines, concentric arcuate lines, or combinations of the same may be readily produced upon the surface to give the desired design thereto, without alteration in the device.

It will further be noted that by removing the holder plates 46 and 48, the base plate 10 only of the device may be employed to mark a single line either straight or arcuate as set forth hereinbefore.

From the foregoing, it will be seen that the device is capable of many time saving uses and modes of employment, and is thus capable of simultaneously producing a plurality of marking lines upon a surface, thus resulting in a great saving from the previous methods employed on such surfaces. Although this device is primarily intended for marking upon quilts, it will be readily understood that the same is capable of use upon other material or surfaces in accordance with the method of use above set forth.

From the foregoing, the manner of construct-

ing and operating the device will be readily understood and further explanation thereof is believed to be unnecessary.

However, since numerous modifications will readily occur to those skilled in the art after a consideration of the foregoing specification and accompanying drawings, it is not intended to limit the invention to the exact construction shown and described, but all suitable modifications and equivalents may be resorted to falling within the scope of the appended claims.

Having described the invention, what is claimed as new is:

1. A quilt marker device comprising an elongated base, a pair of relatively movable elongated clamping members overlying and carried by the base in substantially parallel relation thereto, means for urging said clamping members towards each other to clamp a plurality of pencils therebetween, the adjacent sides of said clamping members having longitudinally spaced pairs of cooperating pencil receiving notches therein, said base having a plurality of spaced apertures therethrough for receiving the lower ends of pencils clamped by the clamping members.

2. A quilt marker device comprising an elongated base having a pair of spaced upstanding standards thereon, a pair of relatively movable elongated clamping members extending between and supported by the standards, means carried by one of the standards for urging said clamping members towards each other to clamp a plurality of pencils therebetween, the adjacent sides of said clamping members having longitudinally spaced pairs of cooperating pencil receiving notches therein, said base having a plurality of spaced apertures therethrough for receiving the lower ends of pencils clamped by the clamping members.

3. A quilt marker device comprising an elongated base having a pair of spaced upstanding standards thereon, a pair of relatively movable elongated clamping members extending between and supported by the standards, means carried by one of the standards for urging said clamping members towards each other to clamp a plurality of pencils therebetween, the adjacent sides of said clamping members having longitudinally spaced pairs of cooperating pencil receiving notches therein, said base having a plurality of spaced apertures therethrough for receiving the lower ends of pencils clamped by the clamping members, said base extending beyond the standards with such extension thereof having a pivot bore therethrough.

4. Quilt marking apparatus comprising an elongated guide rail, an elongated base having first and second spaced upstanding standards thereon, said first standard having a guide shoulder slidably engaging the guide rail, a pair of relatively movable elongated clamping members extending between and supported by the standards in substantially parallel overlying relation to the base, means carried by one of the stand-

ards for urging said clamping members towards each other to clamp a plurality of pencils therebetween, the adjacent sides of said clamping members having longitudinally spaced pairs of cooperating pencil receiving notches therein, said base having a plurality of spaced apertures therethrough for receiving the lower ends of pencils clamped by the clamping members.

5. A quilt marker device comprising an elongated base having a pair of spaced upstanding standards thereon, a pair of relatively movable elongated clamping members extending between and supported by the standards, means carried by one of the standards for urging said clamping members towards each other to clamp a plurality of pencils therebetween, the adjacent sides of said clamping members having longitudinally spaced pairs of cooperating pencil receiving notches therein, said base having a plurality of spaced apertures therethrough for receiving the lower ends of pencils clamped by the clamping members, said clamping members comprising a pair of relatively thin coplanar strips disposed in a plane parallel to and spaced from the base, whereby such strips may be easily flexed towards the base to project the pencils through the apertures in the base.

6. Quilt marking apparatus comprising an elongated guide rail, an elongated base having first and second spaced upstanding standards thereon, said first standard having a guide shoulder slidably engaging the guide rail, a pair of relatively movable elongated clamping members extending between and supported by the standards in substantially parallel overlying relation to the base, means carried by one of the standards for urging said clamping members towards each other to clamp a plurality of pencils therebetween, the adjacent sides of said clamping members having longitudinally spaced pairs of cooperating pencil receiving notches therein, said base having a plurality of spaced apertures therethrough for receiving the lower ends of pencils clamped by the clamping members, said clamping members comprising a pair of relatively thin coplanar strips disposed in a plane parallel to and spaced from the base, whereby such strips may be easily flexed towards the base to project the pencils through the apertures in the base.

ORA ZOE DELL JOHNSON.
